UNITED STATES PATENT OFFICE.

EARLE E. CHAPMAN, OF LOS ANGELES, CALIFORNIA, ASSIGNOR TO MILLER-CHAPMAN COMPANY, A CORPORATION OF CALIFORNIA.

DESIGN FOR A SPARE-TIRE LOCK FOR AUTOMOBILES.

59,062.

Specification for Design.

Patented Sept. 20, 1921.

Application filed November 10, 1920. Serial No. 423,211. Term of patent 14 years.

To all whom it may concern:

Be it known that I, EARLE E. CHAPMAN, a citizen of the United States, residing at Los Angeles, in the county of Los Angeles and State of California, have invented a new, original, and ornamental Design for a Spare-Tire Lock for Automobiles, of which the following is a specification, reference being had to the accompanying drawing, forming part thereof.

The single figure of the drawing is a perspective view of one embodiment of my invention.

This lock is designed to be clamped about a spare tire and consists of two members pivoted together at 1 as shown in the drawing, and locked together at 2 by suitable lock 3.

I claim:

The ornamental design for a spare tire lock for automobiles, as shown.

EARLE E. CHAPMAN.
